(57) **CLAIM**

The ornamental design for cast stone, as shown and described.

DESCRIPTION

FIG. 1 is a photographic showing of a cast stone with a small square face;

FIG. 2 is a photographic showing of a cast stone with a rectangular face;

FIG. 3 is photographic showing of a cast stone having a rectangular face whose width is one half its length; and,

FIG. 4 is photographic showing of a cast stone having a relatively large square face.

The broken lines in the Figures are for illustration purposes only and form no part of the claimed design.
